[54] MANUFACTURE OF HALOPHENOLS

[75] Inventor: **John Brewster Rose**, Letchworth, England

[73] Assignee: **Imperial Chemical Industries Limited**, London, England

[21] Appl. No.: **812,438**

where Z is OH or halogen with a phenol in the presence of anhydrous HF as a catalyst. The compound

[22] Filed: **Jul. 1, 1977**

[30] Foreign Application Priority Data

Jul. 9, 1976 United Kingdom 28674/76

[51] Int. Cl.² **C07C 45/14**

[52] U.S. Cl. ..... **260/591; 260/544 D; 260/515 A**

where X = F, may be made in situ by the reaction of

[57] ABSTRACT

Halophenols of formula

with an alkali metal nitrite in anhydrous HF.

**9 Claims, No Sheets Drawing,
8 Pages Specification**

where X = halogen, are made by condensation of a compound
